UNITED STATES PATENT OFFICE.

BENJAMIN WEXLER, OF BROOKLYN, NEW YORK, ASSIGNOR TO THE PEELLE COMPANY,
OF BROOKLYN, NEW YORK, A CORPORATION OF NEW YORK.

CONTROLLING MECHANISM FOR ELEVATOR-CARS.

1,314,552.

Specification of Letters Patent.

Patented Sept. 2, 1919.

Application filed May 24, 1918. Serial No. 236,288.

To all whom it may concern:

Be it known that I, BENJAMIN WEXLER, a citizen of the United States, residing at the borough of Brooklyn, in the city of New York, county of Kings, and State of New York, have invented certain new and useful Improvements in Controlling Mechanisms for Elevator-Cars, of which the following is a specification, reference being had therein 5 to the accompanying drawings, which form a part thereof.

My invention relates to controlling mechanisms for elevator cars, and more particularly to a mechanism actuated by the opening 15 and closing of the doors of the elevator shaft, in a manner to permit power to be applied to the car only when all of the doors of the shaft are closed.

There has heretofore been used, a controlling mechanism of the type to which my 20 invention relates, wherein the circuit applying power to the elevator car includes therein a make and break mechanism actuated by means common to all of the doors in a shaft.

It has been found in practice that under 25 some conditions of installation, the means for actuating the make and break mechanism can not be set with sufficient accuracy in relation to the several doors of a shaft, to insure the desired accuracy in the timing of 30 the opening or closing of a door, and of the actuation of the make and break mechanism controlling the circuit to the car. Furthermore the connection between the actuating

35 member for the make and break mechanism for the several doors is subject to slight stretch under elongation stresses, which also tends toward a loss of synchronism in the operation of the doors and of the make and break mechanism. When the operation of 40 the doors and the make and break mechanism are not properly synchronized, there is always a possibility that the make and break mechanism may be so set as to permit power 45 to be applied to the car before the doors are properly closed and locked, and that the doors may be opened slightly without actuating the make and break mechanism so as to prevent application of power to the car.

50 With these conditions in mind, I have provided a controlling mechanism of the type above referred to, wherein the slightest initial movement of a door will so actuate

the make and break mechanism in controlling the circuit through which power to 55 actuate the car is derived, as to prevent the application of power to the car, and avoid possibility of a premature actuation of said make and break mechanism when closing the door and thus permit application of power 60 to the car before the door is completely closed.

A controlling mechanism of the type to which my invention relates, utilizes a sliding weight acting upon the make and break 65 mechanism, my invention contemplating the association with this weight of means whereby the make and break mechanism will be actuated to prevent the application of power to the car before the load of the weight is 70 transferred to the connecting strip or cable acted upon by the several doors, and said strip or cable will be relieved from said load before conditions are such as to permit power to be applied to the car. This construction 75 relieves the door from the additional load of this weight when the operator starts to open it, and avoids the necessity for providing an excess movement of the weight with 80 relation to the make and break mechanism, necessary to compensate for structural irregularities in the make and break mechanism and in the various doors, and the resultant slight dwell between the initial movement of the door and the actuation of the make and 85 break mechanism, when opening the door.

The member for actuating the make and break mechanism, is so constructed and arranged, that it positively locks the weight in the position it assumes when the door is 90 closed, and also serves as a lock to prevent the opening of a door until after the make and break mechanism has been so actuated as to prevent application of power to the car.

95 The invention consists primarily in a controlling mechanism for elevator cars embodying therein a controller operative from within a car, a plurality of elevator doors in an elevator shaft, and means to prevent 100 said controller being made operative to apply power to the car, comprising an electric circuit, including therein a single make and break mechanism, a member movably mounted adjacent thereto, a thrust member carried 105 by said movable member and adapted to

operatively engage said make and break mechanism when all of said elevator doors are closed, and connection between said thrust member and each of said elevator doors, whereby said electric circuit is controlled by the opening and closing of any of said doors; and in such other novel features of construction and combination of parts as are hereinafter set forth and described, and more particularly pointed out in the claims hereto appended.

Referring to the drawings:—

Figure 1 is a fragmentary portion of an elevator shaft showing two doors of the truckable type, and having a controlling mechanism made in accordance with my invention, applied thereto;

Fig. 2 is a detailed view upon a larger scale of the make and break mechanism and the movable member actuating same;

Fig. 3 is a detailed view of said mechanism modified to adapt it to a controlling system for elevators employing a solenoid;

Fig. 4 is a view of a portion of an elevator shaft having therein doors of the telescoping type with my invention applied thereto;

Fig. 5 is a similar view showing the invention applied to laterally sliding doors;

Figs. 6 and 7 are respectively a view of a portion of an elevator shaft employing double swinging doors and a cross-sectional view thereof upon a larger scale, a controlling mechanism made in accordance with my invention being shown in connection therewith.

Like letters refer to like parts throughout the several views.

40 In Fig. 1 of the drawings, I have shown an embodiment of the invention as applied to a type of door known as a truckable door, consisting of two door sections, *a* and *b*, arranged at each door opening in the elevator shaft, said sections moving vertically in the same plane, but in the opposite direction, when opening and closing the door. The said sections are provided with a suitable lock *c*, operative when the doors are in the closed position. The two sections are connected by means of suitably mounted cables *d*, insuring this simultaneous movement.

45 The section *b* is provided with a laterally extending hanger bar *b'*, to which the cables *d* are connected. The doors *a* and *b* are mounted upon suitable rails or guides in the usual and well known manner.

50 Ordinarily a series of such doors are mounted in an elevator shaft, the door openings being positioned one above the other, so that the various hanger bars *b'* are all in the same vertical plane and extend parallel with each other. This general construction is old and well known in this art, and 55 merely exemplifies one type of door in con-

nection with which my invention may be employed.

To place the power for the elevator car under the control of the elevator doors, I include in the circuit to the controller *E*, 70 upon the car, a make and break mechanism, including a plurality of coöperating electric contacts, one of which is adapted to have movement in relation to the other, and associate therewith, a movable member carrying a thrust member adapted to operatively engage said movable contact member when said movable member is in a definite relation to said switch mechanism, this thrust member being so controlled and connected with each of the doors in a shaft that when all of the doors are closed, the circuit to the car will be closed, and when any door is open the circuit will be open, preventing the operator from starting the car until that 85 door is again closed.

This mechanism in the form of the invention shown in Figs. 1 and 2, comprises a bridge switch consisting of fixed contacts *e* and *e'* mounted in a box *g* having a bolt opening *g'* in one wall thereof, and a contact *f* mounted upon a movable member *f'* positioned between said fixed contacts and said bolt opening. The pivotal supporting member *f'* is so mounted as to have a normal tendency to separate the contact *f* from the contacts *e* and *e'*, the contact *f* being acted upon by the spring *f²* to compensate for structural variations in the actuating mechanism for said switch and at the same 90 time impart the desired rapid initial impulse to the movable arm *f'* when the actuating mechanism becomes inoperative as to the switch.

95 Mounted in suitable guides adjacent the switch box *g* and at that side thereof, having the bolt opening *g'* therein, is a weight *h* carrying a spring actuated, slidable thrust member *h'* adapted to pass through the bolt opening *g'* and engage the arm *f'*. The 100 said thrust member is acted upon by a spring *h²* and is provided with an extension *h³* adapted to be engaged by one arm of the bell crank lever *h⁴*, pivoted at *h⁵* to said sliding weight. The said weight *h* is connected by means of the flexible strip or cable *i* and the other arm of the bell 105 crank lever *h⁴*, with the several hanger bars *b'*, the said hanger bars ordinarily being made of angle iron, having an opening in one flange thereof through which the strip or cable *i* passes, and has a free sliding fit. The said strip or cable *i* carries a plurality of impact blocks *i'* adapted to engage the under side of said hanger bars respectively, 110 so that as the opening of one door imparts movement to the weight *h* through said strip or cable *i*, and the lever *h⁴*, the blocks *i'* associated with the hanger bars of other doors, merely move from the operative rela- 115

tion thereto, so that the actuation of any door does not interfere with the other doors in a shaft.

To insure the desired movement of the strip or cable i , I provide the lower end thereof with a weight j which will always hold said strip or cable taut, while being of insufficient weight to overcome the tension of the spring h^2 , the tension of which spring 10 is insufficient to sustain the load of said weight h .

Adjacent the switch box g , I provide a stop h^6 adapted to engage the said weight h in a position where the thrust member h' 15 will be accurately positioned in relation to the bolt socket g' . The contacts $e-e'$ and the controller E , are included in the circuit supplying power to the car, by means of the conductor wires $k-k'$.

20 In Fig. 3 of the drawings, I have illustrated the invention as applied to a type of elevator employing a shipper cable, the sole difference in structure between this form of the invention and that shown in Figs. 25 1 and 2 being a reversal of the relation of the contacts e, e' and f so that the circuit instead of being normally closed, will be normally open. In this form of the invention, the terminal wires $k-k'$ instead 30 of leading to the controller in the elevator car, lead to the terminals of the solenoid m , which solenoid controls a clutch member m' for controlling the shipper cable n by which the switch mechanism o is actuated 35 from the car.

In the form of the invention shown in Fig. 4, I have illustrated the invention as applied to a door structure of the telescoping, counterweighted type, in which the two 40 door sections, a^2 and b^2 , have movement in parallel vertical planes and in the same direction, the opening and closing of the doors being facilitated by the counterweight p . In this form of the invention, 45 the blocks i' upon the strip i instead of operatively engaging a hanger bar upon the doors, engage an extension p' upon the counterweight p . In other respects the construction of the controlling mechanism is 50 the same as that shown in Figs. 1 and 2, it being understood, however, that the same manner of connecting the weight h with the door structure, might be employed in connection with an elevator, using a shipper cable, by the modification of the make and 55 break mechanism as shown in Fig. 3 and heretofore described.

In the form of the invention shown in Fig. 5, I have illustrated the application of 60 the invention to an elevator door of the laterally sliding type, this requiring merely the modification of the details in connecting the weight h with the door. The make and break mechanism is not illustrated in 65 connection with this view, since a normally

closed circuit, such as that shown in Figs. 1 and 2, or a normally open circuit, such as that shown in Fig. 3, may be used according to the type of elevator control employed.

In this form of the invention, I connect 70 the strip or cable i with an endless strip q passing around suitable rollers r, r', r^2 and r^3 , arranged in pairs at the top and at the bottom of the elevator shaft. Extending from, and secured to, the reach q^3 of said 75 endless strip q , are branch strips q^2 , extending about rollers s and s' at opposite sides of each door opening, to the reach q^3 upon the other side of the door openings, to which they are secured. Said branch strip or 80 cable passes through an opening in a bracket t carried by the door proper u , having a free sliding fit in said bracket, and is provided with a block v adapted to engage said bracket. 85

Referring now to the form of the invention shown in Figs. 6 and 7, I have shown the invention as applied to double swinging elevator doors, this form of the invention like that shown in Fig. 5, requiring merely 90 the modification of the connection between the weight h and the several doors in the shaft.

In this form of the invention, I employ a strip q having the same general arrangement as illustrated in connection with Fig. 5, this strip being endless and passing about rollers r, r', r^2 and r^3 . The reach q^3 is provided with blocks w^4 adapted to be engaged by rings w^3 carried by extension strips or 95 cables w passing over the roller w' , adjacent the door opening, and the roller w^2 carried by one of the swinging doors u , and being connected with the other swinging door u' of the pair. By this construction it is impossible to open either swinging door section at any door opening without interrupting the circuit to the controller, or closing the circuit to the solenoid, according to the 100 type of control which may be employed. 105

The operation of the herein described device is substantially as follows:—

Referring more particularly to the form of the invention shown in Figs. 1 and 2 of the drawings, when all of the doors are 115 closed, the weight h will rest upon the stop h^6 and the spring h^2 will project the bolt h' through the bolt opening g' , and against the movable arm f' in a manner to force the contact f into engagement with the contacts 120 $e-e'$, and thus close the circuit through which power to actuate the elevator is derived. Said spring will also exert a pull upon the connection strip or cable i which will bring each of the blocks i' thereon into 125 close juxtaposition with its associated hanger bar b' .

It will be observed that when the parts are in this position, as shown in Fig. 1 of the drawings, the make and break mecha- 130

nism is controlled solely by the bolt h' , the load of the weight h being sustained by the stop h^6 so that the function of this weight is merely to insure a synchronized movement of the bolt and of any door in a shaft which is being closed.

When the car stops at any floor of a shaft, however, and the operator opens the door, as the section a moves upwardly, and the section b moves downwardly, the engagement of the hanger bar b' thereon with its associated block i' exerts a pull upon the strip or cable i with the result that the bell crank lever or trigger h^4 is actuated substantially instantaneously with the initial movement of the door to withdraw the bolt h' from its operative relation to the arm f' . After the bolt has been so withdrawn, the weight h is lifted, this movement resulting in a positioning of the bolt which will prevent its reengagement with said arm f' .

Since the bolt h' must be withdrawn to the full extent before lifting power can be applied to the weight h , it is apparent that since a material opening of the doors is dependent upon the lifting of this weight, all of the doors in a shaft will be locked by said bolt until the make and break mechanism has been so actuated as to prevent the application of power to the car.

Since the tension of the spring h^2 is insufficient to sustain the load of the weight h , but greater than that of the weight j , there will be substantially no additional load placed upon the doors during the initial opening movement.

When any door is in the open position, the relation of parts of the controlling mechanism as to the make and break mechanism, and the parts appurtenant thereto, will be as shown in Fig. 2.

When the parts are in this position, power cannot be applied to the car until the opened door is closed, and the construction of the controlling mechanism made in accordance with my invention is such as to make it impossible to apply power to the car until the door has been closed.

The closing movement of the door permits the weight h to descend and causes the block i' associated with the hanger bar of the door, to closely follow said hanger bar until said weight h engages the stop h^6 when the bolt h' will be aligned with the bolt opening g' . The strip or cable i , as the weight comes to rest, is relieved from the load of said weight before the make and break mechanism can be actuated to permit the application of power to the car, the actuation of this mechanism being dependent upon the final closing movement of the door under the control of the spring h^2 . The quantity of movement required to cause the actuation of the bolt h' , is determined by the relative leverage of the two arms of

the bell crank lever h^4 . It is therefore possible to reduce the quantity of movement which a door may have, before preventing application of power to the car, to a minimum.

In closing the doors, the moving inertia thereof is ordinarily such as to insure the doors coming together in the completely closed position, and the parts are so proportioned as to insure the projection of the bolt h' through the opening g' , and against the arm f' , in a manner to close the circuit substantially instantaneously with this impact of the two doors, and so as to cause the interruption of the circuit if the doors rebound after this impact, without the lock e becoming operative to hold them closed. The bolt h' will tend to prevent such a rebound, however.

The striker member g^2 carried by the switch box g , is provided to insure the retraction of the bolt h' in the event of retardation of the weight h sufficiently to permit this bolt to be projected before the weight comes to rest.

The form of invention shown in Fig. 2, operates, as to the elevator doors, identically as heretofore described, the sole difference between the operation of this form of invention and that shown in Figs. 1 and 2, being that with the withdrawal of the bolt h' , upon the opening of the door, the circuit is made instead of being broken, and with the closing of the door the circuit is broken instead of being made. When the circuit is closed the solenoid m is actuated to cause the clutch m' to grip the shipper cable n in a manner to prevent its actuation, and when the circuit is open, the solenoid m will be deenergized, thus permitting the actuation of the clutch member m' in a manner to permit the cable n to be actuated to apply power to a car.

Referring now to the form of the invention shown in Fig. 4, the operation is identical with that heretofore described in connection with Figs. 1 and 2, the sole difference being that the bolt h' is actuated through the strip or cable i by the descent of the counterweight p instead of by the descent of the door itself.

The actuation of the make and break mechanism, in the form of the invention shown in Fig. 5, is identical with that heretofore described, this form of the invention differing from the form shown in Figs. 1 to 4, merely in the manner of actuating the bolt h' through the strip or cable i . When the door u is moved to the right in opening the door, the bracket t will exert a thrust upon the block v , which, through the branch strip or cable g^2 , will move the endless strip or cable q about the various pulleys r , r' , r^2 , and r^3 . This movement of the strip or cable q will, through the strip or cable i , actuate

the bolt h' . The movement of the endless strip or cable q will result from the pull thereon from the branch strip or cable q^2 , thus causing an upward movement of the 5 reach q' and a downward movement of the reach q^3 . During this movement the blocks v associated with other doors in the shaft, will move away from their coöperating brackets t .

- 10 Upon the closing of the door, the weight h and spring h^2 will impart such travel to the endless strip or cable q as to cause the block v of the open door to follow the door in its closing movement, and the blocks v 15 upon other doors to resume their normal position in close juxtaposition to their coöperating brackets.

The operation of the form of the invention shown in Figs. 6 and 7, differs from that of 20 the form shown in Fig. 5 merely in the manner in which the door applies the actuating power to the strip or cable i .

In this form of the invention, if either door x or x' be open, it will exert a pull 25 upon the strip or cable w which, through the ring w^3 , will impart travel to the endless strip or cable q in a manner to actuate the bolt h' and raise the weight h . This results from the passing of the extension strip 30 or cable w about the pulley w^2 upon one door and attaching the end thereof to the other door. With this construction, it is impossible to move either door without exerting a pull upon said strip or cable w , and 35 hence neither door can be opened without developing conditions preventing the application of power to the car, according to the type of control employed. When the doors are open, the parts will be in the position 40 indicated by the dotted lines in Fig. 7.

When any door in the shaft is opened, the several blocks w^4 upon the endless strip or cable q associated with other doors, will move away from the ring w^3 of the branch 45 strip or cable w of that door.

As the door is closed, the stresses upon the endless strip or cable q will be relieved, thus permitting the weight h to descend and the bolt h' to be projected to actuate the make 50 and break mechanism in a manner to permit the application of power to the car. The closing movement of the doors, will create slack in the extension strip or cable w , which slack will be taken up by the movement 55 of the endless strip or cable q during the movement thereof, imparted thereto, by the weight h , the spring h^2 and the connection i .

It will be observed that in a controlling 60 mechanism made in accordance with my invention, the make and break mechanism will be actuated to prevent application of power to the car before any door can have sufficient movement to permit it to be opened to an 65 extent to permit fire to pass from, or to, the

shaft, and that the bell crank lever h^4 , or other trigger mechanism, may be so proportioned and set as to act substantially simultaneously with the initial movement of the door. Since the plunger h' will be withdrawn from its operative relation to the make and break mechanism before the load of the weight h will be transmitted to the strip or cable i , the stresses upon said strip or cable will not be such as to have any tendency 70 toward elongation of the same prior to the actuation of said plunger.

It will also be observed that the plunger h' will be projected through the bolt opening g' by the action of the spring h^2 , and not 80 as a result of the movement of the weight h' , so that there will be a slight dwell after the weight h reaches the limit of its downward movement, before the said plunger becomes operative, during which interval the 85 spring h^2 will impart movement to the strip or cable i and its appurtenances, which movement, however, will be a rapid movement, thus resulting in a quick make or break of the circuit, according to the type 90 of make and break mechanism used.

The make and break mechanism, being controlled entirely by the movement of the doors, may be so set as to avoid any possibility of the application of power to the car, 95 except when the door is closed. While the strip or cable i is accessible to the car operator, it will be observed that it cannot be used by the operator in a manner to permit the application of power to the car so 100 long as a door is open, since its movement, resulting in the actuation of the make and break mechanism to permit application of the power, is not possible without a closing movement of the door.

105 It is apparent that a controlling mechanism made in accordance with my invention is not only capable of application to various types of elevator doors, but may be readily applied to different types of doors in the 110 same elevator shaft.

It is not my intention to limit the invention to the precise details of construction shown in the accompanying drawings, it being apparent that such may be varied 115 without departing from the spirit and scope of the invention.

Having described the invention what I claim as new, and desire to have protected by Letters Patent, is:—

- 120 1. A controlling mechanism for elevator cars embodying therein a controller operative from within a car, a plurality of elevator doors in an elevator shaft, and means to prevent said controller being made operative to apply power to the car, comprising an electric circuit, including therein a single make and break mechanism, a member 125 movably mounted adjacent thereto, a thrust member carried by said movable member and 130

adapted to operatively engage said make and break mechanism when all of said elevator doors are closed, means disposed between said make and break mechanism and 5 said movable member, whereby movement of said member is prevented until said thrust member is disengaged from said make and break mechanism, and a connection between said thrust member and each of said elevator doors, whereby said electric circuit is controlled by the opening and closing of any 10 of said doors.

2. A controlling mechanism for elevator cars embodying therein a controller operative from within a car, a plurality of elevator doors in an elevator shaft, and means controlling the application of power to the car, comprising an electric circuit, including therein a single make and break mechanism 15 consisting of a plurality of electrical contacts, a movable member coöperating therewith and adapted to make and break the circuit therethrough, a switch box having a bolt opening through the wall thereof, 20 said make and break mechanism being mounted within said box, a member movably mounted adjacent said switch box, a thrust member carried by said movable member, and adapted to be moved thereby into, or 25 out of, alinement with said bolt opening, said thrust member being adapted to operatively engage said first named movable member when projected through said bolt opening, and a connection between said thrust 30 member and each of said elevator doors, whereby said electric circuit is controlled by the opening and closing of any of said doors.

3. A controlling mechanism for elevator cars embodying therein a controller operative from within a car, a plurality of elevator doors in an elevator shaft, and means controlling the application of power to the car, comprising an electric circuit, including 40 therein a single make and break mechanism consisting of a plurality of electrical contacts, a movable member coöperating therewith and adapted to make and break the circuit therethrough, a switch box having a bolt opening through the wall thereof, said make and break mechanism being mounted within 45 said box, a member movably mounted adjacent said switch box, a thrust member carried by said movable member, and adapted to be moved thereby into, or out of, alinement with said bolt opening, said thrust member being adapted to operatively engage 50 said first named movable member when projected through said bolt opening, a trigger mechanism operative upon said thrust member, a strip connected with said trigger mechanism and extending adjacent all the doors in a shaft, and coöperating means carried by said strip and each door of a shaft, whereby said electric circuit is controlled by the opening and closing of any 55 of said doors.

trolled by the opening and closing of any of said doors.

4. A controlling mechanism for elevator cars embodying therein a controller operative from within a car, a plurality of elevator doors in an elevator shaft, and means controlling the application of power to the car, comprising an electric circuit, including 70 therein a single make and break mechanism consisting of a plurality of electrical contacts, a movable member coöperating therewith and adapted to make and break the circuit therethrough, a switch box having a bolt opening through the wall thereof, said make and break mechanism being 75 mounted within said box, a member movably mounted adjacent said switch box, a spring actuated thrust member carried by said movable member, and adapted to be moved thereby into, or out of, alinement with said bolt opening, said thrust member being 80 adapted to operatively engage said first named movable member when projected through said bolt opening, a trigger mechanism operative upon said thrust member, a strip connected with said trigger mechanism and extending adjacent all the doors in a shaft, and coöperating means carried by said strip and each door of a shaft, whereby said electric circuit is controlled by the opening 85 and closing of any of said doors.

5. A controlling mechanism for elevator cars embodying therein a controller operative from within a car, a plurality of elevator doors in an elevator shaft, and means 90 controlling the application of power to the car, comprising an electric circuit including therein a single make and break mechanism consisting of a plurality of electrical contacts, a movable member coöperating therewith and adapted to make and break the circuit therethrough, a switch box having a bolt opening through the wall thereof, said make and break mechanism being mounted within 95 said box, a member movably mounted adjacent said switch box, a slideable thrust member carried by said movable member and having a projection thereon, said thrust member being adapted to be moved by said movable member into, or out of, alinement 100 with said bolt opening, a spring adapted to normally project said thrust member through said bolt opening into operative engagement with said movable contact, a strip extending adjacent all the doors in said shaft, a bell crank lever, one arm of which is connected with said strip and the other arm of which is adapted to operatively engage the projection upon said thrust member, and coöperating means carried by said strip and each 110 door of a shaft, whereby said electric circuit is controlled by the opening and closing of any of said doors.

6. A controlling mechanism for elevator cars embodying therein a controller opera- 125

tive from within a car, a plurality of elevator doors in an elevator shaft, and means controlling the application of power to the car, comprising an electric circuit including
5 therein a single make and break mechanism consisting of a plurality of electrical contacts, a movable member coöperating therewith and adapted to make and break the circuit therethrough, a switch box having a bolt
10 opening through the wall thereof, said make and break mechanism being mounted within said box, a sliding weight mounted adjacent said switch box, a slideable thrust member carried by said weight and having a projection thereon, said thrust member being adapted to be moved by said weight into, or out of, alinement with said bolt opening, a stop adapted to arrest movement of said weight when said thrust member is in alinement with said bolt opening, a spring
15
20

adapted to normally project said thrust member through said bolt opening into operative engagement with said movable contact, a strip extending adjacent all the doors in said shaft, a bell crank lever, one arm of which is connected with said strip and the other arm of which is adapted to operatively engage the projection upon said thrust member, and coöperating means carried by said strip and each door of a shaft, whereby said electric circuit is controlled by the opening and closing of any of said doors.

In witness whereof I have hereunto affixed my signature, this 22nd day of May, 1918, in the presence of two subscribing witnesses.

BENJAMIN WEXLER.
